CARTON WITH CARRIER HANDLE

Jack A. Ring, San Leandro, Calif., assignor, by mesne assignments, to The Flintkote Company, a corporation of Massachusetts

Filed Sept. 8, 1960, Ser. No. 54,771

1 Claim. (Cl. 229—52)

This invention relates to cartons, and particularly to an improved form of paperboard carton provided with a handle for enabling the carton to be carried.

Paperboard cartons for canned goods and other articles have, in recent years, been provided with carrying handles of various forms.

Carrying handles heretofore proposed in cartons of this type have for the most part been either in the form of strap members requiring extra stock to be utilized as part of the blank from which the carton is made, or in the form of a separately formed strap member secured by various means to the carton.

It has also been heretofore proposed to form a carrying handle, from the glued overlapping portions of the paperboard blank which constitute the top wall of the carton, by providing weakened lines of separation along those portions, thereby enabling a narrow section of those portions to be pulled upwardly above the top of the carton, to serve as the carrying handle.

The carrying handles as heretofore provided in paperboard cartons, thus entail the use of extra stock, or additional steps of manufacture, or the use of paperboard of substantial strength, or a combination of these.

The principal object of the invention is to provide a carton which may be made of relatively light paperboard, and which is provided with a self-contained carrying handle which will be free of the above-mentioned objections attending the forms of carrying handles heretofore proposed.

Another object of the invention is to provide a carton of the character referred to, wherein the carrying handle is in the form of a single thickness of the paperboard from which the carton is formed, and which will nevertheless be sufficiently strong to serve as the carrying handle for cartons containing relatively heavy articles.

The foregoing and other objects and advantages of the invention will be more clearly set forth in the following specification, reference being made to the accompanying drawings.

In the drawings:

FIG. 1 is a plan view of a carton blank embodying the invention, prior to the folding of the blank into the form in which it may be shipped by the manufacturer;

FIG. 2 is a view in perspective, showing the blank of FIG. 1 after it has been folded and glued into tubular form for shipment;

FIG. 3 is a perspective view of the carton as it appears when set up, filled and closed;

FIG. 4 is a view in cross-section, taken vertically along line 4—4 of FIG. 3;

FIG. 5 is a view, partly in elevation and partly in cross-section, taken along line 5—5 of FIG. 4; and

FIG. 6 is a fragmentary plan view, similar to FIG. 1, illustrating a modification of the invention.

Referring to the drawings, FIG. 1 illustrates, diagrammatically, a blank for forming a carton provided with a carrying handle in accordance with the invention.

The blank, indicated generally by numeral 10, is of rectangular outline and comprises a bottom wall panel 12 and a pair of side wall panels 13 and 14, hinged thereto along parallel fold or score lines 15 and 16, respectively. Inwardly foldable flaps 18 and 19 are connected with the bottom wall panel 12 along transverse hinge or

2

score lines 22 and 23, parallel to one another. Likewise, inwardly foldable flaps 26 and 27 are connected to the side wall panel 13 along the hinge lines 22 and 23, respectively, and inwardly foldable flaps 28 and 29 are connected to side wall panel 14 along the hinge lines 22 and 23, respectively.

Terminal panels 30 and 32 of the blank 10 are connected, respectively, by hinge or score lines 31 and 33 to the side wall panels 13 and 14. Inwardly foldable flaps 34 and 35 are connected to panel 30 along the score lines 22 and 23, respectively. Likewise, inwardly foldable flaps 36 and 37 are connected to the panel 32 along the score lines 22 and 23, respectively.

As will be readily understood, when the blank thus formed is folded along transverse score lines 15 and 33 (or 16 and 31) so that the terminal panel 32 partially overlaps the terminal panel 30, and the overlapping portions are glued to one another, the blank will be in the collapsed or flat tubular form in which it is shipped by the manufacturer to the user.

The tubular form of the blank may be set up into its carton form by folding and gluing one of the sets of opposing pairs of flaps, in accordance with the conventional practice. The carton may then be filled, and the other set of opposed pairs of flaps folded and glued to close and seal the carton.

In order to provide the carton with a carrying handle in accordance with the invention, the end panel 32, which partially overlaps the opposite end panel 30 in the folded or set-up condition of the carton to constitute the top wall thereof, is provided with a relatively narrow, elongated slot 40, disposed preferably parallel to the terminal edge 41 of the blank, and extending entirely across panel 32 and a short distance beyond fold lines 22 and 23, into the flaps 36, 37.

In accordance with the invention, the area of the end panel 32 and its flaps 36, 37, bounded by the terminal edge 41 of the blank, the outer edge 42 and the ends 46 of the slot 40, is left unglued to the corresponding overlapped area of the end panel 30 and its flaps 34, 35, when the blank of FIG. 1 is folded and glued into the tubular form shown in FIG. 2. The thus bounded unglued area 44 of panel 30 provides the carrying handle of the carton, as will be more fully explained below.

To that end, the glue, indicated by the stippling 45 in FIG. 1, is applied in such manner as to preclude its being deposited upon the area which corresponds to the surface area of the handle portion 44. This may conveniently be accomplished by first applying to end panel 30 and flaps 34, 35, along the areas thereof corresponding to area 44, a film of ink of the type not wetted by or which is not receptive of the glue applied to the remaining areas of panel 30 and flaps 34, 35, to be overlapped by panel 32 and flaps 36, 37. Such glue-rejecting inks are well known in the art for use in preventing glue from adhering to selected areas of paperboard or the like.

In consequence of the non-gluing of the handle portion 44 to the overlapped portion of end panel 30 and flaps 34, 35 when the blank is folded and glued in accordance with customary practise, the handle portion 44 will remain free to be lifted away from the underlying end panel 30. When the carton has been erected, filled, closed and sealed, and is positioned as illustrated in FIG. 3, a person may lift and carry the carton by means of the handle 44, simply by inserting the fingers beneath the free, outer edge of handle 44 and pulling upwardly thereon, thereby sufficiently distorting the unglued portion 44 to cause it to bow upwardly so as to serve as the carrying handle for the carton. This position of handle 44 is best illustrated in FIGS. 3 and 5 of the drawings.

In order to impart adequate strength to the handle 44 constructed as above described, a relatively narrow rein-

forcing tape 47, is applied to one of its surfaces. This reinforcement is preferably provided by so-called rayon tape, consisting of adhered adjoining strands or rovings of rayon. In the embodiment of the invention shown in FIGS. 1 and 4, the tape 47 is applied to the bottom surface of the handle 44, the tape extending fully across the width of panel 32 and flaps 36, 37. In the modification of the invention illustrated in FIG. 6, the reinforcing tape, indicated at 47a, is applied to the outer surface of the panel 32 and its flaps 36, 37, so as to be disposed on the outer surface of the handle in the erected carton.

What I claim is:

A paperboard carton, comprising a bottom wall, a pair of opposed side walls hinged at opposite sides of said bottom wall, inwardly folded end flaps hinged to opposite ends of said bottom wall and to opposite ends of said side walls, an end panel hinged to each of said side walls at the end thereof opposite said bottom wall, said end panels being partially overlapped and forming the top wall of the carton, inwardly folded flaps hinged at opposite ends of each of said end panels, the overlapping one of said

end panels having a relatively narrow elongated slot extending lengthwise of said panel, said overlapping end panel and its folded flaps being glued to the overlapped end panel and its folded flaps throughout their mutually confronting surfaces except along the areas thereof bounded substantially by (1) the end edges of said slot, (2) the outermost edge of said overlapping end panel and (3) the outer elongated edge of said slot, said unglued areas of the overlapping end panel being free to be lifted upwardly from the confronting surface of the overlapped panel to provide a carrying handle for the carton extending from said slot toward the hinged end of said overlapped end panel.
